UNITED STATES PATENT OFFICE.

EDMOND LECHAT, OF NANTES, FRANCE.

APPARATUS FOR THE MANUFACTURE OF BRICKS OR BUILDING-BLOCKS.

1,383,131.

Specification of Letters Patent. Patented June 28, 1921.

Application filed March 30, 1921. Serial No. 457,044.

To all whom it may concern:

Be it known that I, EDMOND LECHAT, citizen of the French Republic, residing at Nantes, Loire-Inférieure, in the Republic of France, have invented new and useful Improvements in Apparatus for the Manufacture of Bricks or Building-Blocks, (for which I have filed applications in France, November 11, 1919; Belgium, Nov. 2, 1920; 5 Germany, Nov. 9, 1920; Great Britain, Nov. 9, 1920; Spain, Nov. 9, 1920; Italy, Nov. 10, 1920,) of which the following is a specification.

This invention has for its object an apparatus for the manufacture of bricks or building blocks provided with a facing, which automatically and simultaneously places two varieties of concrete into the molds of the brick and block presses, one of these varieties being used to form a facing upon one or more sides of the bricks or block while the second forms the main body, this apparatus being essentially constituted by a framework supporting the whole of the 15 special mechanism for entraining the endless apron constituting the movable bottom of the distributing troughs provided with adjustable shutters, the material thereof being drawn into feeding chutes and fed thence 20 into conduits or spouts which extend through an opening into the molds of the press and have the same shape as the latter, the sides of these spouts opposite the sides 25 of the block to be faced being disposed inwardly of the corresponding inner sides of said molds, thus leaving a space to receive the high quality facing concrete flowed in from the corresponding chutes, whereas 30 through the intermediary of the distributing troughs for the core material, this latter is flowed into the bottom of the spouts which rest at this moment upon the bottom of the 35 molds.

In the accompanying drawing and by way 40 of example:

Figure 1 is a general view of an apparatus according to the invention mounted upon its base and viewed from the side of the entraining mechanism.

Fig. 2 shows in elevation the movable 50 spouts for the feeding of the concrete for the main body or core of the block.

Fig. 3 is a corresponding plan view.

Fig. 4 is a vertical section of the feeding chutes for the high grade material forming 55 the facing of the block.

Fig. 5 is a plan view of the distributing troughs with movable bottom, also showing the method of entraining the drum for the small side to be faced. 60

As shown in the drawing:

This machine is composed of a framework in wrought or cast iron 1 (Fig. 1) serving to support the entire mechanism of the distributing apparatus as well as the feeding 65 chutes for the facing material.

This framework rests upon and is secured to a base 2 disposed above the press table carrying the molds. In this base is provided an opening to allow the spouts to 70 descend into the molds 22 of the press.

Upon this framework are secured by means of bearings the entraining drums 4 and 5 for the endless aprons 12 and 12^a forming the movable bottom of the troughs 75 6 and 7. The brackets 8 and 9 are also secured thereto. To these brackets are secured the stretchers 10 and 10^a whose bearings are mounted upon slides and are driven back by the springs 11 and 11^a in such manner as to stretch the endless belts 12 and 12^a. 80

The partition 23 prevents the material which becomes detached from the aprons when returning empty from falling into the trough placed below. 85

The return pulley 14 is also secured to this framework.

The gear wheels 15 and 16 are keyed to the shafts of the drums 4 and 5 (Fig. 1).

The gear wheel 17 (Fig. 5) is actuated by 90 the tractive effort exerted upon the chain 18 (Fig. 1).

This gear 17 is of the free wheel type, that is, the rotary motion of the teeth is transmitted to the shaft to which the wheel is keyed only in one direction. 95

The gear 19 (Fig. 1) is loose upon its shaft and is only used here to provide for

the engagement of the chain 20 upon the gear wheel 15. The troughs 6 and 7 are maintained by easy friction upon the endless belts constituting their movable bottom, this being effected by means of braces 8 and 9 secured to the machine frame and to the brackets.

10 The drums 4 and 5 receive their movement from a chain which is connected to a stud secured to the gear wheel of the press, and itself keyed to the shaft actuating the dies of said press.

15 During a portion of the rotation of said gear wheel, the chain 18 is actuated thereby and actuates in turn the gear wheel of the drums. All the gears are properly connected together by endless chains 20 and 28 in such manner that the movement given by them to the endless belts shall be convergent.

20 The movement of the endless belts forming the bottom of the troughs 6 and 7 being thus provided for said belts draw along toward the chutes 13 and the spouts 3 the material which fills the troughs and the latter is thus properly distributed and placed in position.

25 To give passage to the material fed into the troughs 6 and 7 there are provided in the sides of the trough opposite the chutes 30 and the spouts, openings provided with movable shutters 25 and 25^a (Fig. 1) whose movement will vary the amount of material distributed at each revolution of the drums.

35 The spouts feeding the rough or core material have the same shape as the molds of the press. The sides *a* and *b* (Fig. 3) of these spouts which are opposite the sides of the block to be faced are set inwardly 40 relative to the inner sides of the mold by 8 to 12 millim. whereby a space *c* will be left between the sides of the spout and the inner sides of the mold. This space receives and is filled with the high grade material 45 delivered into the chutes 13 from the endless belts of the distributing troughs.

50 During the same time, the endless belts of the distributing troughs for the rough material having been given the same movement, this material is dropped to the bottom of the spouts which at this time rest upon the bottom of the molds (Fig. 2).

55 It will result that within the spouts is disposed the rough material, while on the outside and in the spaces between the inner sides of the mold and the outer sides of the spouts is disposed the facing material.

60 The quantity of material delivered at each rotation having been regulated by means of the shutters 25 and 25^a and these quantities being sufficient to fill the molds, it will then suffice to vertically remove the spouts in order that the two kinds of material shall support each other in their respective positions.

The compressing action is now all that is required in order to obtain the product after removal of the mold.

65 The vertical lifting of the spouts is carried out in the automatic process by means of a lever which is actuated by a suitably shaped cam properly secured to the shaft carrying the dies of the press. This lever is connected to the spouts by a rod 26 (Fig. 1) pivoted at both ends.

70 In their rise and descent the spouts are vertically guided by the uprights 21 (Figs. 1, 2 and 3). These spouts being connected together by bearings working with easy friction upon the uprights, they cannot vary 80 during their movements, thus affording the proper working for the entire apparatus.

75 The operation of the apparatus is as follows: The latter having been disposed in the proper position above molds of the press 85 and this position having been adjusted once for all, if the press is started, at the moment when the dies commence to be lifted, the cam having been suitably disposed, the lever actuated thereby is lifted and then 90 holds in this position the spouts 3, this prevailing until the moment when another mold would come under the dies. At this moment, the lever leaves the boss of the cam (not shown in the drawing) and the spouts 95 will fall by their own weight to the bottom of the molds which have now come under the same. At this same moment the traction takes place on the chain 18 and thus the drums 4 and 5 commence to move, entraining into the spouts 3 and the chutes 13 the material disposed upon the endless aprons.

100 When the compression is finished, the dies resume their upward movement; the traction stud for the chain having been suitably disposed in order that at this moment the stud will be at its point farthest away from the apparatus, the endless belts will stop and the boss of the cam now acts again 110 upon the actuating lever of the spouts which latter will rise along the slides. The spouts being no longer engaged in the molds, the cycle of the press may recommence without inconvenience and all the movements of the 115 apparatus will be automatically repeated.

120 In the apparatus which are not to be mounted upon automatic presses with revolving plate, the placing of the apparatus in position will be carried out by the workman who will rotate it upon its support about a suitable pivot.

125 In this case also, the distribution will be effected by operating a handle which is substituted for the free wheel pinion used in the apparatus mounted upon entirely automatic presses.

130 The rotary movement of the drums for the small sides A (Fig. 5) is effected by a pair of bevel gears 27. One of the gears is

keyed to the shaft of the drum of the system of distribution of the high grade material for a large size, while the other gear wheel of the same size as the first is keyed 5 to the drum of the system of distribution for the smaller side; the endless belt is held in the same manner as the other endless belts.

It is thus evident that the entire system 10 of distribution will operate and stop at the same time.

The synchronism of the movements of the press, the spouts and the belts obtained by a suitable adjustment which will vary with 15 each type of press.

It is of course understood that this invention is not limited to the constructional dispositions above described which are given solely by way of example and which may 20 comprise all modifications which do not depart from the principle of the invention.

Having now described my invention, what I claim as new and desire to secure by Letters Patent is:

25 1. A feeding apparatus for brick or building block presses, comprising in combination upper troughs containing the concrete used to form the main body or core of the brick or block, lower troughs containing the concrete used to form a facing upon one or more sides of the brick or block, endless 30 aprons constituting the movable bottom of the distributing troughs, each trough being provided with adjustable shutters, spouts vertically moved extending through an opening into the mold of the press, a series of feeding chutes leading the first of said qualities of concrete into said spouts and another series of feeding chutes leading the 35 second of said qualities of concrete around said spouts.

2. A feeding apparatus for brick or building block presses, comprising in combination upper troughs containing the concrete used 45 to form the main body or core of the brick or block, lower troughs containing the concrete used to form a facing upon one or more sides of the brick or block, endless aprons constituting the movable bottom of the distributing troughs, each trough being provided with adjustable shutters, rotatable drums supporting said aprons, spouts vertically moved extending through an opening into the molds of the press, a series of feeding chutes leading the first of said qualities of concrete into said spouts and another series of feeding chutes leading the second of said qualities of concrete around said spouts.

3. A feeding apparatus for brick or building block presses, comprising in combination upper troughs containing the concrete used to form the main body or core of the brick or block, lower troughs containing the concrete used to form a facing upon one or more sides of the brick or block, endless aprons constituting the movable bottom of the distributing troughs, each trough being 50

sides of the brick or block, endless aprons constituting the movable bottom of the distributing troughs, each trough being provided with adjustable shutters, rotatable drums supporting said aprons, means for imparting to said drums an intermittent rotary movement, spouts vertically moved extending through an opening into the molds of the press, a series of feeding chutes leading the first of said qualities of concrete into 55 said spouts and another series of feeding chutes leading the second of said qualities of concrete around said spouts.

4. A feeding apparatus for brick or building block presses, comprising in combination upper troughs containing the concrete used to form the main body or core of the brick or block, lower troughs containing the concrete used to form a facing upon one or more sides of the brick or block, endless 60 aprons constituting the movable bottom of the distributing troughs, each trough being provided with adjustable shutters, rotatable drums supporting said aprons, means for actuating the press and for imparting to said 65 drums, a rotary movement, chains and pinions connecting said drums together, one of said pinions being of the free wheel type, a chain actuating this pinion and receiving its movement from said wheel, spouts vertically moved extending through an opening into the molds of the press, a series of feeding chutes leading the first of said qualities of concrete into said spouts and another series of feeding chutes leading the second 70 of said qualities of concrete around said spouts.

5. A feeding apparatus for brick or building block presses, comprising in combination upper troughs containing the concrete used to form the main body or core of the brick or block, lower troughs containing the concrete used to form a facing upon one or more sides of the brick or block, endless 75 aprons constituting the movable bottom of the distributing troughs, each trough being provided with adjustable shutters, spouts vertically moved extending through an opening into the molds of the press, a series of feeding chutes leading the first of said qualities of concrete into said spouts and another series of feeding chutes leading the second of said qualities of concrete around said spouts, means for actuating the press and said drums, and means for lifting by 80 intermittence said spouts.

6. A feeding apparatus for brick or building block presses, comprising in combination upper troughs containing the concrete used to form the main body or core of the 85 brick or block, lower troughs containing the concrete used to form a facing upon one or more sides of the brick or block, endless aprons constituting the movable bottom of the distributing troughs, each trough being 90

provided with adjustable shutters, spouts vertically moved extending through an opening into the molds of the press, a series of feeding chutes leading the first of said qualities of concrete into said spouts and another series of feeding chutes leading the second of said qualities of concrete around said spouts, means for actuating the press and said drums and comprising rotatable mem-

bers, a cam on one of said members, a rod 10 actuated by said cam and lifting said spouts by intermittence, said spouts falling by their own weight to the bottom of the molds of the press.

In testimony whereof I have signed my 15 name to this specification.

EDMOND LECHAT.
